UNITED STATES PATENT OFFICE.

JULIAN B. HYMER, OF ZARAH, KANSAS.

VEHICLE-WHEEL.

1,168,076.

Specification of Letters Patent. Patented Jan. 11, 1916.

Application filed April 18, 1912. Serial No. 691,705.

To all whom it may concern:

Be it known that I, JULIAN B. HYMER, a citizen of the United States, and a resident of Zarah, in the county of Johnson and State 5 of Kansas, have invented certain new and useful Improvements in Vehicle-Wheels, of which the following is a specification.

My invention relates to improvements in vehicle wheels.

10 The object of my invention is to provide a vehicle wheel which is simple in construction, which has the resiliency of the ordinary wheel provided with a pneumatic tire, which is not liable to puncture, is efficient in operation, and which will possess great durability.

15 In the accompanying drawings I have illustrated a structure provided with my improvements, and which comprises the preferred form of my invention.

20 The novel features of my invention are hereinafter fully described and claimed.

Figure 1 is a view partly in elevation, partly in vertical section, and partly broken away. Fig. 2 is a vertical section on the 25 line *a*—*b* of Fig. 1. Fig. 3 is a perspective view of one of the radially movable blocks.

Similar characters of reference designate similar parts in the different views.

1 designates a hub adapted to receive an 30 axle not shown. Secured to the opposite ends of the hub 1 are two side members 2, preferably of sheet steel, which are secured to the hub by tie bolts 3. Encircling the hub 1 is a support comprising, preferably an 35 annular member 4 having a peripheral groove 5 in which is located a resilient member, comprising, preferably, an inflatable rubber tube 6 provided with a filling tube 7 which extends laterally through one of the 40 side plates 2, and is provided at its outer end with a cap 8.

Arranged around the inflatable tube 6 are a plurality of radially movable members 45 comprising blocks 9 the inner ends of which are adapted to bear against the tube 6, when said tube is inflated, as shown in Figs. 1 and 2. The blocks 9 are adapted, when the inflatable tube 6 is deflated to have their inner ends bear against inwardly turned annular flanges 10, which are provided on the outer 50 edges of the annular member 4. When the blocks 9 are moved inwardly so as to bear against said flanges, the adjacent sides of the blocks 9 will be in contact with each other, thus forming a support for a rim 11 located 55 between the plates 2 and having on its inner

side an annular groove 12 in which the blocks 9 are slidably radially. When the tube 6 is inflated and the blocks 9 are in the outer positions, the outer ends of the blocks 60 will all contact with the rim 11.

The rim 11 is provided with transverse holes 13 through which extend spacing tubes 14, the ends of which bear against the inner sides of the plates 2. Extending through 65 the spacing tubes 14 are tie rods 15 provided with nuts 16, said tie rods being provided to secure the plates 2 against the ends of said tubes 14. The sides of the blocks 9 are provided with recesses 17 which are adapted 70 to receive the spacing tubes 14 and tie rods 15.

In the operation of my invention, the inflatable tube 6 is inflated in the usual manner through the tube 7. The tube 6 will 75 then hold the blocks 9 out of contact with the annular member 4, so that said blocks will have a resilient support in the use of the wheel. The periphery of the rim 11 may have an annular groove in which may be 80 located a tire, 18, preferably of rubber. The tie rods 15 with the spacing tubes 14 serve to limit the circumferential movement of the blocks 9 between the side plates 2. In case the inflatable tube 6 becomes deflated, the 85 blocks 9 will be supported by the flanges 10. With the inflatable tube 6 located as described and shown, there will be no liability of puncture, while the wheel will still have the resiliency afforded by an inflatable tube. 90 The tube 6 being fully incased will be protected from external injury and the weather, and will, therefore, be possessed of great durability.

I do not limit my invention to the structure described and illustrated, as modifications, within the scope of the appended claims, may be made without departing from the spirit of my invention.

Having thus described my invention, what 100 I claim and desire to secure by Letters Patent, is:—

1. In a vehicle wheel, two side members, an annular support secured to and between 105 said members, radially independently movable members arranged around said support and adapted when moved inwardly a predetermined distance to contact with said support, resilient means supported by and encircling said support and normally holding 110 the radially movable members out of contact with said support, the radially movable

members being adapted to contact with each other when in contact with said support, and a rim encircling the radially movable members and having an inner annular groove in which said radially movable members are mounted.

2. In a vehicle wheel, two side members, a ring support secured centrally to and between said side members and having a peripheral groove and inwardly turned peripheral flanges at opposite sides of said groove, resilient means mounted in said groove of said ring support, radially independently movable members arranged around and adapted, when the resilient means is in the expanded condition to contact at their inner ends therewith, and adapted, when the resilient means is collapsed a predetermined amount to contact with said flanges, and a rim encircling and in contact with said blocks when the resilient means is expanded.

3. In a vehicle wheel, two side members, a ring support secured centrally to and between said members and having a peripheral groove and inwardly turned flanges at opposite sides of said groove, a pneumatic resilient tube mounted in said groove, radially independently movable members between said side members and having their inner ends adapted to contact with the pneumatic tube when the tube is expanded, and adapted, when the tube is collapsed to a predetermined amount to contact with said flanges, and a rim mounted on the outer ends of said radially movable members.

In testimony whereof I have signed my name to this specification in the presence of two subscribing witnesses.

JULIAN B. HYMER.
